CONTROL LEVER OR WRENCH FOR GAS
METER INLET COCKS

Benjamin Herskovits, New York, N. Y.

Application March 23, 1942, Serial No. 435,794

1 Claim. (Cl. 251—152)

This invention relates to an attachment for the inlet cock for a gas meter.

More particularly, my invention relates to the provision of a control device for the control cock on the inlet pipe to the gas meter which will permit quick and accurate shut-off.

My invention contemplates facilitating the control of the gas supply at the main inlet pipe line to the meter so that during any emergency, such as that occasioned by violent jars caused by detonation of bombs or any other hazard, the main inlet line to the household or other establishment may be quickly placed in the shut-off position and therefore cut off the supply of gas and minimize fire hazard from this source.

In accordance with present installations, the inlet cock for a gas meter is provided with a wrench spindle having one movable lock receiving flange and one stationary lock receiving flange. To turn this inlet cock to the open or closed position, usually requires that one have available a medium size monkey or Stillson wrench as well as in certain instances to have available some means of reaching this cock where the gas meter is disposed in difficultly accessible locations.

Accordingly, it is an object of my invention to provide a wrench or control lever for a gas meter control cock which may be quickly and simply affixed in position upon the wrench spindle of the cock and be available quickly and accurately to operate the cock to the open or closed position.

More particularly my invention relates in the combination with a gas meter control cock of a control lever which may be made of inexpensive material and be readily attached to the wrench spindle of the inlet cock of the gas line for its operation during any emergency.

Still more particularly, my invention relates to the provision of a control lever for standard gas inlet cocks to be found adjacent gas meters wherein the control cock which has a movable lock receiving flange and a stationary lock receiving flange is availed of for mounting the control lever to facilitate assembly with this instrumentality and increase the engaging relationship of the control lever with the wrench spindle while utilizing the lock receiving flanges to act as guides in the accurate positioning of the control cock to the open or closed position.

To attain these objects and such further objects as may appear herein or be hereinafter pointed out, I make reference to the accompanying drawing, forming a part hereof, in which:

Figure 1 is a face view of a control lever attach-

ment in accordance with my invention, mounted upon the inlet cock of a gas line;

Figure 2 is a side elevation thereof;

Figure 3 is a section taken on the line 3—3 of Figure 1;

Figure 4 is a face view of another embodiment of my invention;

Figure 5 is a detail of the stop determining link of the embodiment illustrated in Figure 4;

Figure 6 is a general assembly of a gas meter with my control lever in position.

Making reference to the drawing, I illustrate my invention in connection with an inlet cock 10 positioned in the gas line 11, normally to be found adjacent the gas meter of households or other establishments. In this cock, there is customarily included a wrench spindle 12 for turning the valve of the cock. The spindle carries a flange 13 formed with an orifice 14. The casing of the cock carries a flange 15 having an orifice 16. This assembly is familiar, it being noted that the flanges 13 and 15 may be positioned in alignment to align the orifices 14 and 16, thereby to close or shut-off the gas supply. In this position the orifices 14 and 16 may have a lock passed therethrough and for this reason the flanges 13 and 15 are referred to by me as lock flanges.

In my experience, the turning off or opening of the inlet cock during any emergency may be made a comparatively simple operation; in fact, as simple as the switching on and off of an electric switch, without the unusual care normally encountered in operating the inlet cock or the employment of rather expensive wrenches such as a monkey wrench or Stillson wrench.

In accordance with my invention, I provide a control lever 17, one end whereof 18 may be provided with a link 19 and an operating handle 20 to render the lever accessible if the inlet cock 10 is disposed in positions normally requiring a step ladder.

The opposite end of the lever 17 is formed with an orifice 21 arranged to receive the wrench spindle 12. Spaced from the orifice 21, I provide a second orifice 21a arranged to be aligned with the orifice 14 on the lock flange 13. A screw 22 may then be passed through the orifice 21a and 14 respectively engaging on the interior face of the lock flange 13 a link 23 having a lug 24. The link 23 is sufficiently thin to be received in the space 25 lying between the lock flange 13 and the lock flange 15. The lug 24 is so extended that it lies in the path of the stationary lock flange 15. While I may rely upon the screw 22 engaging the link 23, to hold the control lever 17 mounted

upon the movable lock flange 13, I may additionally prevent displacement of the control lever 17 from its position upon the wrench spindle 12 by wedging cross rods 26 through the orifice 27 normally to be found in the wrench spindle.

These cross rods 26 may be conveniently in the form of cut-nails driven in opposite directions through the orifice 27 to become wedged therein.

With the installation as described a downward movement of the lever 17 will serve to shut-off the inlet cock. This downward movement is continued to the point where the lug 24 engages the upper face 24a of the stationary lock flange 15. Thus, the lug 24 serves quickly to limit the movement of the control lever without any special care to see that the lock flanges are in alignment, making certain that the valve is in the closed position.

Coordinateately the end of the lever is provided with a lug 28 extended in the path of the lock flange 15 and arranged in the upward position of the control lever to engage the lower face 28a of the lock flange 15.

It will thus appear from the construction just described that I have provided a wrench for the gas meter control cock which may be easily and facilely installed and that no special experience is necessary in order to bring the control valve into the fully closed or open position since the lugs 24 and 28 are extended so that movement of the lever will align the lock flanges and the valve control, thereby, into an accurate fully open or closed position. Likewise, it will be observed that my operating lever may be made from rather inexpensive metal stampings, not requiring the rigid and weighty construction of medium sized monkey or Stillson wrenches, normally employed for turning or shutting off the inlet cocks of gas meters of this character.

The extension of the link 23 to engage the movable lock flange 13 provides an extended bearing surface making the employment of heavy stock material for the control lever unnecessary.

In Figures 4 and 5 I have shown another embodiment of my invention wherein the control lever 17a is formed with an orifice 31 arranged to receive the wrench spindle 12. In this construction, however, I provide a generally L shaped link 23a which may be received within the clearance space 25. The link 23a has its branch 30 formed with an orifice 31 and is disposed on the interior face of the flange 13 bringing the orifice 31 in alignment with the orifice 14 of the lock flange 13. In this position a screw 22 is disposed through the orifice 21a formed on the control lever 17a, thereby holding the control lever 17a in position on one face of the lock flange 13 and holding the link 23a on the opposite face of the lock flange 13. The branch 30 is extended to form adjacent its end a lug 24b. This lug is transversely extended so that it projects in the plane of the stationary lock flange 15. The branch 32 of the link 30 has its end 33 formed with a lug 28b. This lug is laterally extended to intersect the plane passing through the stationary lock flange 15.

It will be observed that by this form of construction a simple control lever 17a is provided requiring very little special machining.

The link 23a provides the lugs 24b and 28b to determine the stopping positions of the inlet

cock wrench spindle. Thus, in the position shown in Figure 4, the operating lever 17a is disposed to position the lug 28b to the point where it engages the lower face 28a of the stationary lock flange 15. Downward movement of the lever in a clockwise direction turns the wrench spindle to the point where the lug 24b engages the upper face 24a with the stationary lock flange 15, thereby guiding the control lever 15 to accurately close the inlet cock.

It will be observed that I have provided a simple and economical gas meter control device which may be quickly and facilely installed and be manipulated accurately by the most inexperienced housewife to thereby minimize hazards in improper operation of this control cock of the gas meter. My device thereby provides an installation which may be quickly made to meet the present emergency where detonation of bombs may make it necessary to turn off the gas of the meter.

While my device is designed primarily to meet such emergencies, it will be understood that it forms a convenient appliance where normal operation may make it necessary quickly and facilely to turn off the gas supply without having to hunt around for an instrumentality to effect this operation.

While I have described the link 19 and the operating handle therefor of such nature as to provide means of reaching the control cock in difficultly accessible locations and make the same of rigid material for push and pull operation, it will be understood that this member may be located for operation from floor height and thereby facilitate its location for control in dim illumination or total darkness, eliminating the hazard of flames or sparks to disclose the whereabouts of this control member for cutting off the flow of gas; also while a rigid rod is disclosed in close proximity for push and pull operation, this rod may be extended at greater lengths for remote control operation from a point exterior of the room where the meter is disposed, and for this purpose cable or chain control is contemplated by me for operation from any point above, below or laterally thereof, with adequate provision for guiding the cable or chain to the lever arm, as will be readily understood by the skilled worker.

Having thus described my invention and illustrated its use, what I claim as new, and desire to secure by Letters Patent, is:

In a gas meter control cock, having a movable lock flange mounted upon a wrench spindle, and a stationary lock flange mounted upon the casing, the combination therewith of a link associated with said flanges and an operating lever for the wrench spindle of said cock combining with said movable flange to hold said lever upon the spindle and providing at least one lug serving as a stop for a portion of the operating lever in the operation of said spindle by engagement with the stationary flange accurately to position said flanges in the fully open position of said cock upon opening movement of said cock and serving accurately to align said lock flanges to the fully closed position of said cock in the converse operation of said lever.

BENJAMIN HERSKOVITS.
